DESIGN FOR AN AERIAL FOR AUTOMOBILES

David A. Vaughan, Woodstock, N. Y.

Application October 9, 1937, Serial No. 72,104

Term of patent 3½ years

To all whom it may concern:

Be it known that I, David A. Vaughan, a citizen of the United States, residing at Woodstock, in the county of Ulster and State of New York, have invented a new, original, and ornamental Design for an Aerial for Automobiles, of which the following is a specification, reference being had to the accompanying drawing, forming part thereof, in which is shown in side elevation an aerial for automobiles showing my design. The char-

acteristic feature of the design resides in the musical symbol ornaments.

The device is formed of thin flat wire-like members lying in the same plane and has no material third dimension.

I claim:

The ornamental design for an aerial for automobiles, as shown and described.

DAVID A. VAUGHAN.
